(Cl. D26—14)

To all whom it may concern:

Be it known that I, John S. Dougherty, a citizen of the United States, residing in Jackson Heights, in the county of Queens and State of New York, have invented a new, original, and ornamental Design for a Lens Attachment for Television Receiving Sets, of which the following is a specification, reference being had to the accompanying drawing, forming part thereof.

Figure 1 is a top plan view of a lens attachment for television receiving sets showing my new design.

Figure 2 is a side elevation.

Figure 3 is a front elevation.

Figure 4 is a section on the line 4—4 of Figure 3.

I claim:

The ornamental design for a lens attachment for television receiving sets, as shown.

JOHN S. DOUGHERTY.
